US0D1067072S

(12) **United States Design Patent** (10) **Patent No.:** **US D1,067,072 S**
(45) **Date of Patent:** **** Mar. 18, 2025**

(54) **OPTOELECTRONIC SENSOR**

(71) Applicant: **SICK AG**, Waldkirch (DE)

(72) Inventors: **Patrick Erlewein**, Vörstetten (DE);
Axel Schonhardt, Waldkirch (DE);
Michael Scheickenpflug, Freiamt (DE);
Michael Kaspar, Ettenheim (DE)

(73) Assignee: **SICK AG**, Waldkirch (DE)

(**) Term: **15 Years**

(21) Appl. No.: **35/519,133**

(22) Filed: **Nov. 8, 2023**

(80) **Hague Agreement Data**

Int. Filing Date: **Nov. 8, 2023**

Int. Reg. No.: **DM/233241**

Int. Reg. Date: **Nov. 8, 2023**

Int. Reg. Pub. Date: **Nov. 24, 2023**

(51) **LOC (15) Cl.** **10-05**

(52) **U.S. Cl.**

USPC **D10/75**

(58) **Field of Classification Search**

USPC D10/75, 78, 79, 83

CPC G01S 17/42; G01S 7/4817; G01S 17/04

(57) **CLAIM**

The ornamental design for an optoelectronic sensor as shown and described.

DESCRIPTION

1. Optoelectronic sensor

1.1 : Perspective

1.2 : Front

1.3 : Back

1.4 : Top

1.5 : Bottom

1.6 : Left

1.7 : Right

The broken lines shown are included for the purpose of illustrating portions of the optoelectronic sensor and form no part of the claimed design.
